AUTOMATIC LIGHTING AND DISPENSING DEVICE

Albert Disbrow Claggett, Denver, Colo., assignor
of one-half to C. D. Titus and one-half to Hor-
ace G. Claggett, Denver, Colo.

Application February 2, 1933, Serial No. 654,908

4 Claims. (Cl. 312—86)

This invention relates to a device for holding, dispensing and lighting cigarettes, and while more particularly designed for use in automobiles and other automotive vehicles, it is not of course limited to this use as it would also be found valuable as a desk or home dispenser.

The principal object of the invention is to provide a simple and inexpensive, yet highly efficient device which will deliver cigarettes one at a time, and if desired will light the delivered cigarette.

Another object of the invention is to provide a device of this character which will quickly light a cigarette without the use of suction devices.

A further object is to so construct the device that the cigarettes can be readily and easily placed therein.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a face view of the improved dispensing and lighting device. In this view the cover plate is partially broken away to illustrate the position of the cigarettes therein.

Fig. 2 is a left side view thereof.

Fig. 3 is a plan view thereof with the cover plate partially broken away.

Fig. 4 is a vertical section taken on the line 4—4, Fig. 5, with the cover plate in place.

Fig. 5 is a section taken on the line 5—5, Fig. 4, with the cover plate removed.

The invention comprises: a frame 10 preferably stamped from sheet metal. The frame 10 is formed with two vertical flanges 11 projecting from its rear to contact with and space the device from any suitable supporting surface. The frame 10 is provided with a slotted opening 12 for receiving any suitable clamping device and with screw holes 13 which may be employed if it is desired to permanently attach the device to a supporting surface.

A cigarette holder 14 is positioned on the front of the frame 10. The holder 14 comprises: a sheet metal stamping having an open front with two inwardly turned flanges 15 to maintain a vertical pile of cigarettes in place. The holder

14 is provided with suitable holes, through which access may be had to the holes 12 and 13 in the frame 10 as shown in Fig. 5. A pair of ears 16 are stamped from the material of the holder 14 and project rearwardly through suitable slots in the frame 10. A wire spring 17 extends between the ears 16 and over a hook-shaped projection 17' on the frame.

It will be noted that this provides a flexible hinge construction for the holder and, since the ears are positioned adjacent the top, allows the bottom of the holder to be swung outwardly away from the frame 10. The front of the holder 14 is closed by means of a slidible cover plate 29 which extends rearwardly at each side 15 of the holder and which is provided with inwardly extending flanges 33 at the back to maintain it in place.

The cigarettes are supported in the holder by means of a forwardly projecting shelf 18 formed on the frame. The frame 10 extends downwardly from the shelf 18 to support a metal shield 19 by means of suitable screws 20. An operating shaft 21 is supported in the shield 19. The shaft 21 terminates on the front in an operating handle 22 fixed thereon. A receiving trough 23 is secured adjacent its one extremity on the shaft 21 so that movement of the handle 22 from the horizontal to the vertical position will swing the trough 23 also from a horizontal to a vertical position. The inner side of the trough 23 is relatively low and is positioned immediately below the shelf 18.

The base member 19 also supports an insulator 24 of porcelain or electrical insulating material. The insulator 24 carries a heating element 25 formed of nichrome or other suitable resistance wire. One terminal of the heating element 25 terminates in a binding screw 26, the other terminal terminates in a contact spring 27 secured on the insulator 24. The short extremity of the trough 23 is provided with a downwardly extending lip 28. When the trough approaches the vertical, the lip 28 contacts with the spring 27 to close the circuit to the frame 10, which is grounded when in use.

Operation

Let us assume the holder 14 is filled with 50 cigarettes, such as indicated at 30. The user grasps the holder between the thumb and fingers and draws it outwardly. This causes the lower extremity of the holder to swing over the trough member 23, as shown in broken line in 55

Fig. 2, so as to deposit the lowermost cigarette therein. The spring 17 then swings the holder back to the normal position over the shelf 18. The handle 22 is now turned vertically, to the broken line position of Fig. 1. This allows the 5 delivered cigarette to slide from the trough 23 to a vertical position on the heating element 25 where it rests by gravity. The upward movement of the handle 22 closes the electrical circuit between the lip 28 and the spring 27 so that 10 the element heats sufficiently to ignite the tobacco at the lower end of the cigarette.

It will be noted that the bottom of the shield 19 is open around the heating element and is 15 curved about the cigarette, as shown by the curved portion 31. This results in a stack action, that is, the heating element 25 heats the air within the curved portion 31 causing it to rise therein and draw fresh air in through the 20 open bottom. This air circulation has been found to be very effective in immediately igniting the tobacco.

It will also be noted that the forward edge of 25 the trough member 23 is relatively wide so that the user can not conveniently reach the cigarette while the trough is in the vertical position. He, therefor, must turn the trough member back to the horizontal position before removing the cigarette. This requires the user to 30 open the electrical circuit before he can reach the cigarette and reduces the liability of accidental and damaging over heating. When the cigarettes are exhausted, it is only necessary to slide the cover plate 29 upwardly to remove 35 it. A new pile of cigarettes can then be placed behind the retaining flanges 15 of the holder 12.

While a specific form of the improvement has been described and illustrated herein, it is 40 desired to be understood that the same may be varied, within the scope of the appended claims, without departing from the spirit of the invention.

Having thus described the invention, what is 45 claimed and desired secured by Letters Patent is:—

1. A device for dispensing and lighting cigarettes comprising: a frame member extending first downward to form a vertical back portion, thence forwardly to form a shelf, thence again 50 downward to form a depending portion; an open bottomed container hinged adjacent the top of said back portion and normally lying thereagainst and terminating above said shelf portion; a shield secured to and extending forwardly from said depending portion; a shaft 55 extending through said shield and said depending portion; a receiving trough secured at its one extremity on said shaft and normally lying horizontal below said shelf portion; a handle secured on said shaft exteriorly of said shield; and a heating element carried by said depending portion within said shield below the shaft 60 extremity of said trough.

2. A device for dispensing and lighting cigarettes comprising: a frame member extending first downward to form a vertical back portion,

thence forwardly to form a shelf, thence again 5 downward to form a depending portion, an open bottomed container hinged adjacent the top of said back portion and normally lying thereagainst and terminating above said shelf portion; a shield secured to and extending forwardly from said depending portion; a shaft 10 extending through said shield and said depending portion; a receiving trough secured at its one extremity on said shaft and normally lying horizontal below said shelf portion; a handle secured on said shaft exteriorly of said shield; a heating element carried by said depending portion within said shield below the shaft extremity of said trough; and a vertical, open-bottomed enclosure formed in said shield about 15 said heating element to create a vertical current of air thereby.

3. A device for dispensing and lighting cigarettes comprising: a frame member extending 20 first downwardly to form a vertical back portion thence forwardly to form a shelf, thence again downward to form a depending portion; an open bottomed container hinged adjacent the top of said back portion and normally lying 25 thereagainst and terminating above said shelf portion; a shield secured to and extending forwardly from said depending portion; a shaft extending through said shield and said depending portion; a receiving trough secured at its 30 one extremity on said shaft and normally lying horizontal below said shelf portion; a handle secured on said shaft exteriorly of said shield; an insulating block supported by said depending portion within said shield; a heating 35 element carried on said block below the shaft extremity of said trough; an electric contact for said heating element projecting upwardly from said block so as to be contacted by said trough when the latter is turned toward the 40 vertical position.

4. A device for dispensing and lighting cigarettes comprising: a frame member extending first downward to form a vertical back portion, thence forwardly to form a shelf, thence again 45 downward to form a depending portion; a shield secured to and extending forwardly from said depending portion; a shaft extending through said shield and said depending portion; a receiving trough secured at its one extremity on 50 said shaft and normally lying horizontal below said shelf portion; a handle secured on said shaft exteriorly of said shield; and a heating element carried by said depending portion within said shield below the shaft extremity of said trough; a holder; ears formed on said holder 55 projecting through slots adjacent the top of the back portion of said frame member; a hooked projection on the back of said portion; and a spring member extending between said ears 60 and over said hooked projection so as to normally hold said holder against said frame member and yet allow it to be swung forwardly over said trough member.

ALBERT D. CLAGGETT.
